US00D474234S

(12) United States Design Patent (10) Patent No.: US D474,234 S
Nelms et al. (45) Date of Patent:  May 6, 2003

(54) CREDIT CARD AND CASE

(75) Inventors: David Nelms, Lake Forest, IL (US);
Betty Schick, Lake Villa, IL (US); Kim Wilson, Highland Park, IL (US)

(73) Assignee: Discover Financial Services, Inc.,
Riverwoods, IL (US)

() Term: 14 Years

(21) Appl. No.: 29/146,805

(22) Filed: Aug. 16, 2001

(51) LOC (7) Cl. 19-08

(52) U.S. Cl. D19/9

(57) CLAIM

The ornamental design for a credit card and case, as shown and described.

DESCRIPTION

FIG. 1 is a top plan view of the credit card and case showing the credit card separately for purposes of illustration;

FIG. 2 is a side elevational view of FIG. 1;

FIG. 3 is a top plan view showing the case separately for purposes of illustration;

FIG. 4 is a side elevational view of FIG. 3;

FIG. 5 is a top plan view of the credit card and case shown together in assembled condition; and,

FIG. 6 is a perspective view of FIG. 5 in combination with a key and ring.

The broken lines showing environment in FIG. 6 are for illustrative purposes only and form no part of the claimed design.
